UNITED STATES PATENT OFFICE.

PATRICK B. DELANY, OF SOUTH ORANGE, NEW JERSEY.

TELEGRAPHY.

No. 874,745.

Specification of Letters Patent.

Patented Dec. 24, 1907.

Application filed June 13, 1903. Serial No. 161,343.

To all whom it may concern:

Be it known that I, PATRICK B. DELANY, a citizen of the United States, residing at South Orange, county of Essex, State of New Jersey, have invented certain new and useful Improvements in Telegraphy, of which the following is a specification.

The invention relates to that part of a wireless telegraph system by which the electro magnetic waves or signal impulses passing through the primary receiver devices are made manifest or ultimately recorded.

The local instrument affected or actuated by reason of variation of resistance in a coherer, in a wireless system, has heretofore been under the control of a force, either electro magnetic or the reaction of a retractile spring, serving to return and retain it in normal position, but which must be overtaken to effect actuation of the instrument when a signal wave or impulse is received. Such local instrument has for instance been an electro magnet with a neutral armature having a retractable spring, or a polarized instrument having a magnetically biased armature. With either of these arrangements, the effective local current due to variation of resistance in the coherer, must be sufficient to cause the actuation of the armature of the local instrument against the opposing force exercised by its retractable spring in the one case, or its magnetic bias in the other: and, as the return movement of the armature after the coherer has been decohered should, for efficient working, be substantially equal in time period, and at least equal in force to the forward movement under action of the current, a considerable part of the energy or pull of the electro magnet is wasted in moving the armature against the opposing force of its retractable spring or magnetic bias. Perhaps, as much as one-half of such energy is so wasted.

In its broad aspect the invention is not limited to that type of wireless coherer or primary instrument in which the resistance is decreased on the passage of a signal wave, but is preferably employed therewith and such combination or organization is specifically an important part of this invention.

Further the invention is preferably so organized that the movable part of the relay shall be subject to no bias magnetic or mechanical.

An organization specially well adapted to carry out this invention comprises a polarized relay having an armature neutral or unbiased as to position and wholly unhampered in its response to the current impulses in the coils of its magnet. Such an armature having been moved to its closed side, or its marking or signaling contact, and having performed its function of control of the coherer, tapper or other local instrument, is immediately withdrawn to its open or spacing position by a suitable current admitted to the winding of the magnet. Admission of the latter current may be controlled in any appropriate way. Naturally, the current should become effective co-incidently with the action of the de-coherer; and, preferably, the circuit of said current is controlled by an electro magnet in circuit with the decoherer magnet either in series or parallel instead of by the tapper or armature lever of the de-coherer. By such an arrangement the local instrument or relay controlled by the coherer or primary instrument of variable resistance responds more readily with less current change in its winding than if its armature were biased either magnetically or by a retractile spring: and the return of its armature is quick and positive, being in no measure dependent on a retractile force, necessarily weak, slow and uncertain, because of the necessity of adjusting it to such point that it may be overcome on the passage of an electro magnetic wave or signal impulse through the coherer. In this improved system, the retractile force may be many times greater than the attracting force since its power is withdrawn instantly its function has been performed.

The accompanying drawing illustrates, diagrammatically, an embodiment of this invention that experience has shown to be practical and efficient.

Figure 1 is a diagrammatic view illustrating the operation of the invention; and, Fig. 2, shows an ink recorder as the final receiver.

a is the vertical conductor connected with one terminal of the coherer *b*, the other terminal of which is connected to earth at *E*. Connected to the terminals of the coherer and, consequently, in shunt around it, is a circuit *c* containing a local battery *d* and an adjustable resistance *e* and including one coil or winding of a multiply wound polar-

ized relay *f*, the other winding of which is including in a circuit *g* including a local battery *h* and controlled at the contact *i*, *j*; the latter being an insulated piece mounted on the armature lever *k* of an electro magnet *l*. *m* is the de-coherer magnet (to the armature lever of which the coherer is attached) included in the circuit *n*, containing a local battery *n'*, and having one terminal connected with the unbiased armature of the relay *f* and the other with the contact stop *o* of such armature, the opposite or limiting stop of which is marked *p*. The batteries *d*, and *h* are so connected in their respective circuits as to produce movement of the armature lever of the relay *f* in opposite directions. The magnet *l* is connected in a circuit *g* whose terminals are joined to the sides of the circuit *n*, and such magnet is, therefore, in parallel with the de-coherer magnet *m*. When a signal caused by an electro magnetic wave passes through the coherer, its resistance being thereby lowered, the increased flow of current in the local circuit *c* shunting the coherer causes the armature of the polarized instrument *f* to be attracted to its marking, or signal contact *o*, thereby completing the circuit of the de-coherer magnet *m*, and also that of the local magnet *l* whose armature lever, being attracted, brings contact *j* against contact posts *i*, closing the circuit *g* and reversing the polarized relay and quickly bringing its armature back against the open or spacing stop *p*. The circuit of the de-coherer magnet *m* and magnet *l* having been opened when the armature lever of relay *f* left its marking contact *o*, that armature is again free to be attracted when the next variation of resistance of the coherer occurs. Dots may thus be represented by one or more quick vibrations of the armature lever of relay *f*, while dashes may be formed by six or seven quick vibrations—all according to the manner of manipulation or transmission at the distant station. These signals may be made manifest by any suitable final receiver; or, may be caused to actuate a relay for re-transmission into another circuit. This may be conveniently accomplished at the armature lever *k* of the magnet *l*. Thus a local circuit *r* may be closed at the contact *s* against which the armature lever *k* bears when the magnet *l* is energized. The drawing indicates means for making a chemical record. Ordinary recording styluses *t* *u* are connected with the terminals of this local circuit and bear upon a traveling strip of chemically prepared paper, *v*, *w* being the local recording battery. The several vibrations of which each dot and each dash may be composed, may be caused to appear as a solid mark on the chemically prepared paper by providing capacity for the circuit *r*; as, for instance, by means of the condenser *x* connected in the circuit, as shown. By such

introduction of "capacity" the retardation of the circuit may be made such as to produce the result stated.

The breaking of the local circuit at the contact *o* produces more or less arcing and, consequently, a tendency of the armature lever of *f* to stick upon the contact. When ordinary retractable springs, or a magnetically biased armature, are employed, this sticking seriously interferes with working because if the retractile force be sufficient to overcome the sticking without hesitancy, then the adjustment will not be so sensitive for reception of the signals. In this improved organization, the retractile force may be, as already stated, many times stronger than the attracting force; consequently, the most delicate adjustment or condition is afforded. Since, in this organization, it is impossible for the armature lever *f* to remain against the contact *o*, the apparatus is always in condition to respond to the slightest rise of current, the attention of the operator being thereby attracted when a distant operator wishes to communicate.

In Fig. 2, the local circuit *r* completed at contact *s* includes an electro-magnet *y*, the armature lever of which carries an ink roll operating against a traveling paper *z*.

1 and 2 indicate retardation coils placed in local circuits *c* in each side of the instrument *f*. Their function is the usual one and is well understood.

I claim as my invention:

1. In wireless telegraphy, the combination with the primary variable resistance device, of a receiver instrument having a movable part, a local circuit including the instrument and controlled by variation of resistance of the primary device; whereby said part is moved to make a signal on the reception of a signal wave or impulse that affects the variable resistance device, and means for, on the completion of the signal, developing a force locally for returning the movable part to normal position.

2. In wireless telegraphy, the combination of the primary variable resistance device, an electro magnetic device, its armature, a local circuit including the electro-magnetic device and controlled by the variable resistance device; to cause attraction of the armature on reception of a signal wave or impulse, and a second local circuit acting on the completion of the signal to retract the armature to its normal position.

3. In wireless telegraphy, the combination with the primary variable resistance device, of a receiver instrument having a movable unbiased part, a local circuit including said instrument and controlled by variation of resistance of the primary device, whereby said part is moved to make a signal on reception of a signal wave or impulse and means for, on the completion of the signal, developing

a force locally for returning the movable part to normal position.

4. In wireless telegraphy, the combination with a coherer, resistance of which is decreased on the reception of a signal wave or impulse, a local circuit controlled thereby, an armature attracted from normal position to signaling position by such local circuit on the reception of a signal wave or impulse, and a second local circuit normally open but closed on the completion of a signal and acting to retract the armature to its normal position.
5. In wireless telegraphy, the combination with a coherer, resistance of which is decreased on the reception of a signal wave or impulse, a local circuit controlled thereby, an unbiased armature attracted from normal position to signaling position by such local circuit on the reception of a signal wave or impulse, and a second local circuit normally open but closed on the completion of a signal and acting to retract the armature to its normal position.
- 20 6. In wireless telegraphy, the combination

with a coherer, of a local polarized instrument having an unbiased armature, one winding controlled by variation of resistance in the coherer to move the armature lever to the signaling or marking position, and a second circuit automatically controlled to move the armature to its opposite or normal position.

- 30 7. In wireless telegraphy, the combination with a coherer, of a polarized local instrument having an unbiased armature, means for energizing such polarized instrument in one sense or direction by current impulse controlled by the coherer to move the armature to the marking or signaling position, and means for automatically energizing such instrument in a reverse sense or direction to restore the armature to normal position.

In testimony whereof, I have hereunto subscribed my name.

PATRICK B. DELANY.
